PHILIP N. BRAUN, OF SYRACUSE, NEW YORK, ASSIGNOR TO THE PROSPERITY COMPANY INC., OF SYRACUSE, NEW YORK, A CORPORATION OF NEW YORK

DRYING ATTACHMENT FOR PRESSING MACHINES

Application filed January 20, 1928. Serial No. 248,254.

This invention relates to pressing machines and has for its object a particularly simple and efficient means whereby the moisture can be removed from the article being pressed and the padding on one of the pressing elements in a comparatively short time, and also whereby the vapor generated in the garment or article from the moisture therein by the head of the pressing elements, is free to ventilate or pass off during the pressing operation and as it is generated.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying my invention.

Figure 2 is an enlarged fragmentary side elevation showing the machine open and the ventilating plate in its position assumed when air is being blown to dry the garment.

Figure 3 is a plan view on a reduced scale of the machine.

Figure 4 is an enlarged detail view of the mechanism for holding the ventilating and presser plate in its position assumed when overlying the work on the buck.

Figure 5 is an enlarged fragmentary sectional view of the ventilating and presser plate.

In pressing cloths and garments, particularly nap goods which contain moisture or which are moistened either by dampening cloth or by steam projected thereinto during the pressing operation, the steam or moisture is trapped in the garment until the press is opened, and furthermore the vapor or steam condenses in the garment when the press is opened so that the air must be passed through the garment for a much longer time to remove the condensation. In fact it is not possible to remove all the condensation by passing air through the garment, particularly if the current of air is created by suction or the outer air drawn through the garment.

The invention comprises a ventilating and

presser platen element associated with the movable pressing element or head and overlying the pressing face thereof, means for blowing air through the stationary pressing element or buck, the article thereon and the 55 ventilating and presser platen element, the press being so formed that the air or vapor can ventilate comparatively easy there-through and pass out through the edges of the platen element when the press is closed, and directly through the platen element when the press is open and the plate held onto the work.

The pressing machine may be of any suitable form, size or construction. That here 65 shown includes a head 1 movable toward and from the buck 2, carried by a suitable bracket 3 which is mounted upon a bench or table 4, the latter being supported on a suitable frame or legs 5.

The upper pressing element 1 is usually formed hollow to have an internal chamber which heats the head, and is also provided with means for projecting steam through its 75 pressing face onto the garment to moisten the garment. The buck may also be provided with steam heating and projecting means, if desired.

As the idea of moistening a garment with moistened cloths and projecting steam out 80 or through the garment is very old and well known, further description of this feature is though to be unnecessary, particularly as it forms no part of this invention, except that some sort of moistening means for moistening the article being pressed is provided in tailor machines or machines for pressing nap goods or knit goods.

The head 1 is actuated in any suitable manner and is here shown as carried by a yoke lever 6 pivoted at 7 between its ends, this lever being here shown as actuated by a pedal lever 8 pivoted at 9 to the frame and having an upwardly extending arm 10 pivoted at 11 95 to a link 12 which is pivoted at 13 to the rear arm of the lever 6, the pedal 8 having a plate 14 at the front end.

The parts 10 and 12 constitute a toggle. Obviously, when the pedal 8 is depressed, the 100

toggle will be straightened and the press closed.

The press is here shown as held closed by the latching mechanism designated generally 15, which is tripped by a kick off lever 16. The press is opened by a counterweight 17 and spring 18. The opening and closing movement of the toggle is limited by stops 19 and 20 coacting with a stop 10^a on the lever 10 arm 10.

The features thus far specifically described are old and well known in the art and forms no part of this invention.

21 designates the ventilating and presser platen element forming the subject matter of the invention, this being associated with the head 1 and normally overlying the pressing face thereof. It is so formed as to have communicating passages extending lengthwise 15 and crosswise therethrough, and also through its upper and lower faces, these communicating passages permitting the free escape of vapor and air when the press head is closed, and particularly the escape of vapor as it is 20 generated by the heat from head 1 from the moisture in the garment or for permitting the escape of vapor or steam when it is projected from the head onto the garment when the head is closed or projected through the 25 garment from the lower buck when the head is closed.

The presser platen element 21 is here shown as made up of a plurality of layers 22 of reticulated material or wire mesh, the upper 30 and lower layers being continuous and passing around a rod or wire 23 which forms a frame for the platen element, which frame fits around the edge of the head 1 and provides a marginal flange 24 around the edge of the head 1, or in other words, a seat or depression for receiving head 1.

25 designates a carrier for the ventilating and presser platen element, this carrier being in the form of a yoke lever which is preferably pivoted coaxially with the yoke lever 6.

The platen element 21 is held against the head 1 and caused to follow the head 1, when unrestrained, by means here shown as a spring 26 connected at one end to the frame, and its other end to a rearwardly extending arm 27 on the supporting lever 25. Means is provided for automatically holding the presser platen element onto the work on the buck 1 during the opening of the press, such means being manually releasable. The holding means here shown comprises two members coacting with a ratcheting action, one member being a segment 28 pivoted at 29 to the frame and having ratchet teeth 30 and the other member being a pawl 31 coacting with the ratchet teeth.

The member 28 is actuated by the support 25 and is connected thereto by a link 32 pivoted at 33 to the arm 27 and at 34 to a rock

arm 35 associated with segment 28. The pawl 31 is pivoted at 31^a to the frame and has a rock arm 31^b which is manually operable. This means as illustrated is a link 31^c extending to the front of the machine where it is provided with a handle 37.

A spring 38 acts on the link 36 or the pawl 31 to urge the pawl toward the ratchet teeth. Obviously, during the closing movement of the head, the ratchet teeth 30 will ratchet along the pawl 31 and when the head is closed, the pawl will hold the segment 28, and hence the platen element 21 from upward movement with the head 6 and upon the forward pulling the handle 37, the pawl will be operated to release the segment 28 permitting the spring 26 to move the platen element 21 upwardly against the head.

The lower buck 2 is usually provided with a padding and with means for blowing a drying fluid as air through the padding 39, the article thereon and the ventilating and presser element 21.

40 is a pipe for air, this pipe extending upwardly through the bracket 3 to a distributing channel 41 in the buck, which channel is provided with suitable outlet perforations extending lengthwise of the buck and under the padding 39. The flow of air through the pipe 40 from an intake pipe 42 is controlled by a suitable valve located in a casing 43 and operated by a push button 44. Any suitable valve may be used.

In operation, the press is closed on the work on the buck 2 and the moisture or vapor generated in the garment by the heat from the head 1 or the vapor projected into the garment, easily escapes without being trapped in the garment, through the ventilating presser platen element. When the press is opened by operating the kick off pedal 16, the ventilating platen element remains on the garment and upon the depression of the button 44, air will be blown through the garment quickly removing the vapor and moisture therein.

The platen element 21 is provided with a suitable handle 45 by means of which it may be pulled down onto the garment at any time without actuating the head.

I am aware that it is well known to dry the garment or article, and the padding in laundry and garment pressing machines, but believe I am first to provide a ventilating and presser platen element through which the moisture and vapor is always free to pass off comparatively unrestrained, and also, the first to provide means for blowing air, when the press is open, directly through the padding and the article thereon without disarranging the garment.

By my invention, a garment can be pressed and dried with considerable time saving, because in machines heretofore used the moisture became trapped in the garment when

the head is closed, and is subject to condensation by the colder outer air when the head is opened, or subject to the condensation by colder air when the air is drawn or sucked through the garment.

5 5. What I claim is:

1. A pressing machine comprising a buck, a head movable toward and from the buck, a foraminous ventilating and presser platen element overlying the pressing face of the head, and means for blowing air through the buck, the work thereon and the ventilating and presser platen element, said element being formed to provide outlets for air and vapor at its edges.

10 2. A pressing machine comprising a buck, a head movable toward and from the buck, a ventilating and presser element overlying the pressing face of the head, and means for blowing air through the buck, the work thereon and the ventilating and presser element, said element having communicating passages extending lengthwise and crosswise thereof and also through its upper and lower faces, said passages communicating with each other and permitting the free escape of vapor and air when the press is closed.

15 3. A pressing machine comprising a buck, a head movable toward and from the buck, a ventilating and presser element overlying the pressing face of the head, and means for blowing air through the buck, the work thereon and the ventilating and presser element, said element comprising a plurality of layers of reticulated material.

20 4. A pressing machine comprising a buck, a head movable toward and from the buck, and an open work ventilating and presser element overlying the pressing face of the head and having its openings extending throughout the thickness thereof and through the edge of the element, means for blowing a fluid through the buck, the article thereon and said element.

25 5. A pressing machine comprising a supporting frame, a buck, a head movable toward and from the buck, an open work ventilating and presser element to overlie the buck when the head is open, a carrier for said element, said carrier being supported by the frame and means for blowing a fluid through the buck, the work thereon and said element.

30 6. A pressing machine comprising a supporting frame, a buck, a head movable toward and from the buck, an open work ventilating and presser element to overlie the buck when the head is open, a carrier for said element movably supported by the frame, means tending to hold said element against the head and cause the element to follow the head, and means for blowing a fluid through the buck, the work thereon and said element.

35 7. A pressing machine comprising a sup-

porting frame, a buck, a head movable toward and from the buck, an open work ventilating and presser element to overlie the buck when the head is open, a carrier for said element movably supported by the frame, means tending to cause the element to follow the head, means for automatically holding said element onto the work on the buck during the opening of the press, and means for blowing a fluid through the buck, the work thereon and said element.

40 8. A pressing machine comprising a buck, a head movable toward and from the buck, an open work ventilating and presser element associated with the head and separable therefrom to overlie the buck when the head is open, a carrier for the element, means tending to cause said element to follow the head, means for automatically holding the element onto the work on the buck during the opening of the press, means for blowing a fluid through the buck, the work thereon and said element, and operator operated means for releasing said element holding means.

45 9. A pressing machine including a buck, a head movable toward and from the buck, a ventilating and presser element movable with the head and separable therefrom, a carrier for said element for supporting the element independently of the head and the buck, means tending to cause said element to follow the head, a lock including two coacting members, and connections between one member and the carrier to move the same during the movement of the carrier, the other lock member coacting with the former to normally hold it and the carrier, and operator-operated means connected to said other member to release the same.

50 10. A pressing machine comprising a buck, a head movable toward and from the buck, an open work ventilating and presser element extending between the head and the buck, a carrier for said element, means tending to cause said element to follow the head and return the element against the head, a lock including two coacting members, and connections between one member and the carrier to move the same during the movement of the carrier the other lock member coacting with the former to hold it and the carrier from movement, and operator operated means connected to said other member to release the same, and means for blowing a fluid through the lower buck and the article thereon and the said element.

55 11. A pressing machine comprising a buck, a head movable toward and from the buck, a foraminous ventilating and presser element movable by the head and separable therefrom, a carrier for the said element for supporting the element independently of the head and buck, means tending to cause the said element to follow the head and to return the said element against the head, a lock in-

cluding two coacting members and connections between one member and the carrier to move the same during the movement of the carrier, and operator-operated means connected to the other member to release the same.

12. A pressing machine comprising a buck, a head movable toward and from the buck, a foraminous ventilating and presser element movable by the head, a carrier for the said element, means tending to cause the said element to follow the head and return the element against the head, a lock including two coacting members, and connections between one member and the carrier to move the same during the movement of the carrier, and operator-operated means connected to the other member to release the same, and means for blowing a fluid through the lower buck and the article thereon and said element.

13. A pressing machine including cooperative pressing members including a buck, and a head movable toward and from the buck, and a foraminous ventilating and presser element overlying the pressing face of the head, the element being formed to provide for the escape at its edges of a fluid passing through the said element, means for supporting said element, and means for allowing a fluid through one of the pressing members and the element.

14. A pressing machine comprising cooperative pressing members including a buck, and a head movable toward and from the buck, and a ventilating and presser element overlying the pressing face of the head, said element having communicating passages extending lengthwise and crosswise thereof and also through its upper and lower faces, said passages communicating with each other permitting the free escape of vapor and air when the press is closed, and means for blowing a fluid through one of the members and said element.

15. A pressing machine comprising cooperative pressing members including a buck, and a head movable toward and from the buck, and a ventilating and presser element overlying the pressing face of the head, said element being formed of a plurality of layers of reticulated material, and means for blowing a fluid through one of the members and said element.

In testimony whereof, I have hereunto signed my name, at Syracuse, in the county of Onondago and State of New York, this 10th day of January, 1929.

PHILIP N. BRAUN.
